UNITED STATES PATENT OFFICE.

JOHN P. SUNDIN, OF ARCATA, CALIFORNIA.

GARMENT-HANGER.

No. 863,236.

Specification of Letters Patent.

Patented Aug. 13, 1907.

Application filed March 25, 1907. Serial No. 364,328.

To all whom it may concern:

Be it known that I, JOHN P. SUNDIN, a citizen of the United States, residing at Arcata, in the county of Humboldt and State of California, have invented a new 5 and useful Garment-Hanger, of which the following is a specification.

The present invention relates to improvements in garment hangers, and it has for its object to provide a device of this character that is adapted to support a suit, 10 that is to say, the coat and vest, and the trousers, in orderly condition, the device being capable of supporting the trousers either in their normal or an inverted position, as may be desired, the device being so constructed that it may be folded to adapt it for use in a 15 suit case for traveling purposes.

To these and other ends, the invention consists in certain improvements and combinations and arrangements of parts, all as will be hereinafter fully described, the 20 novel features being pointed out particularly in the claims at the end of the specification.

In the accompanying drawings, Figure 1 is a perspective view of a garment hanger constructed in accordance with my present invention. Figs. 2 and 3 show the different modes of attaching the trousers to the hanger in 25 order that the latter may be suspended either in normal or inverted positions. Fig. 4 is a view of the hanger in folded condition. Fig. 5 is a detail perspective view of the trousers attaching devices. Fig. 6 is a sectional view of one of the trousers attaching slides.

Corresponding parts in the several figures are indicated throughout by similar characters of reference.

In the present embodiment of the invention, the garment hanger embodies a coat form which is preferably jointed at an intermediate point to enable it to be 30 folded into compact form for packing or traveling purposes, the form in the present instance embodying a pair of segmental members 1 and 2 having a curvature conforming to the shoulders of an average coat in order that they may receive the latter and support it in its proper form. These members are pivotally connected in the present instance by means of a hinge 3 of any desired form, which serves to connect their proximate ends, and into the lower edge of the member 1 is fitted a vertical portion 4 of a supporting hook 5, the latter being 35 rotatable relatively to the members in order that it may fold closely between them when the members are in folded condition. It is preferable to provide suitable means for retaining the members in opened relation, the means provided for this purpose embodying, 40 in the present instance, a hook 6 pivoted to the side of

one of the members and arranged to coöperate with a headed projection or screw 7 on the other member, the catch thus provided being arranged at that side of the form opposite to the hinge, and when the hook and projection are engaged, the members composing the coat 55 form cannot be folded.

On the underside of the coat form toward each end are provided the guides 8 and 9, the latter being composed, in the present instance, of wire of suitable gage having one end fitted into a longitudinally extending 60 aperture 10 in the end of the coat form, and having its opposite end turned upwardly and fitted into a transversely extending aperture 11, that portion of the guide between its attached ends being slightly spaced from the lower edge of the form. These guides are adapted 65 to support the trousers suspending devices, and these devices, in the present instance, are each composed of a pair of loops 11 and 12 having relatively large openings at their tops to receive the head of the suspender button, the lower portion of the opening being reduced and 70 adapted to receive the thread or other button fastening means, the reduced portion engaging behind the button to prevent its disengagement. These loops are employed for supporting the trousers in a position corresponding to that position occupied by the trousers 75 while being worn, and as they coöperate with the suspender button, it is unnecessary to employ clamping devices of any kind. These loops are preferably so supported that they may be swung in a vertical plane to clear those devices that are adapted to support the 80 trousers by engaging their lower edges, these loops being supported, in the particular embodiment shown, by the rolled ends 13 and 14 formed by a strip of sheet material, these rolled portions embracing the upper journal portions 15 and 16 of the loops. 85

Intermediate portions of the strip are bent or doubled upon themselves to form a pair of loops 17-18, and journaled in these loops are the arms 19-20 which carry the devices for engaging the lower ends of the trousers. The portion of the strip between the loops 90 19 and 20 is formed into a loop 21, and the latter is adapted to fit upon and operate longitudinally of their respective guides, sufficient looseness being provided between the guide and the loop 21 as will produce a locking action between these parts when a force is applied at a distance from the slide engaging loop, although the devices may be adjusted freely longitudinally of the guide when the pressure is applied at a point adjacent to the loop 21. The strip of material, thus bent to provide pivotal connections for the loops 100

11 and 12 and the arms 19 and 20, is bound by a ring or band 22, and constitutes a slide at each end of the coat form, the slides being adjustable relatively to one another in order that they may accommodate trousers 5 of different dimensions.

The arms 19 and 20 have pointed stems 23 and 24 that are directed outwardly from the opposite ends of the coat form to form pins or projections adapted to enter the lower end of the trouser leg and engage the 10 material thereof at the inside, the enlargements 25 and 26 serving to limit the movement of the projections and thus prevent perforation of the material of the garment.

In using a garment hanger constructed in accordance with my present invention, the trousers may be suspended in a normal or an inverted position, the ordinary suspender buttons being utilized when the trousers are to be supported in an upright position. In this case, the buttons are passed through the relatively large openings in the loops 11 and 12, the narrowed portions of the latter engaging the thread or other fastening of the button to prevent disengagement of the latter, and while the suspender buttons are thus engaged by the supporting loops, the attaching devices 25 carrying the loops are moved outwardly toward the ends of the form in order that the garment may be stretched to free it of wrinkles, the binding or clamping action between the attaching devices and their respective guides serving to retain the former in adjusted 30 position.

When it is desirable to suspend the trousers in an inverted position, the pointed projections 23 and 24 are inserted into the lower edges of the trouser legs and engaged therewith at the front and rear where the usual crease occurs, and while these devices are thus engaged, the attaching devices are moved toward the ends of the form, thereby stretching the trouser legs so that they may hang without folds, the attaching devices being automatically locked in adjusted position 40 by the binding action between them and their respective guides.

While one or more pairs of trousers are thus suspended on the hanger, a coat or waistcoat, or both, may be hung over the coat form in the usual way, so that the 45 hanger is capable of accommodating an entire suit of clothes.

When it is desirable to pack the hanger into a suit case, the catch 6 is disengaged from its coöperating projection 7 and the members composing the coat form 50 may be folded about the pin into doubled relation, and this shortens the length of the device by one half. However, although it is generally preferable to employ a foldable form by reason of its compactness, it will be understood that the invention is not so limited, as the 55 form may be composed of a single rigid member, and, moreover, the invention is capable of being applied to the ordinary coat hanger.

A garment hanger constructed in accordance with my present invention serves the dual purpose of a coat 60 and trousers hanger, and the trousers attaching devices are so constructed that they are not only adjustable in order that they may be correctly fitted to garments of

different sizes, but they are also capable of supporting the trousers in either a natural or an inverted position, and as these devices operate automatically to hold 65 themselves at the proper adjusted position, the hanger may be manipulated with the greatest facility, which is more or less essential in a device of this character, and, moreover, the device may be manufactured so cheaply that it can be sold at a reasonable price, as 70 the relatively adjustable slides carrying the trousers attaching devices may be formed of sheet material by the use of dies.

What is claimed is:—

1. A garment hanger comprising a form having guides 75 extending longitudinally thereof, and a pair of slides provided with upper bearing portions slidably engaging the guides and having depending bearing portions, of a pair of garment attaching devices for each slide, the said devices having journals arranged parallel to the guides 80 and coöperating with the bearing portions of the respective slides for permitting pivotal movement of the garment attaching devices relatively to the respective slides on axes substantially parallel to the said guides.

2. A garment hanger having guides extending longitudinally thereof, slides mounted to operate on the respective guides, and a set of garment attaching devices for each slide comprising a pair of loops and a pair of pointed stems, the loops and stems having journals extending parallel to the guides and coöperating with the 90 respective slides as bearings for permitting independent pivotal movement of the loops and stems on axes substantially parallel to the said guides.

3. The combination with a suitable hanger having 95 longitudinally extending guides thereon, of a pair of trouser attaching devices each embodying a slide adjustable longitudinally on the said guides and having means coöperating automatically with the guides for retaining the slides in different adjusted positions, and a pair of 100 pointed stems pivotally attached to each slide on axes parallel to the guides, the stems on one slide being extended in a direction opposite to that of the stems on the other slide and circumferential garment engaging enlargements of yielding material surrounding the said stems.

4. The combination with a suitable hanger having guides thereon, of slides provided with upper bearing portions adjustable longitudinally on the respective guides and coöperating with the latter to lock the slides in different adjusted positions, and a pair of loops pivotally attached to each slide on axes parallel to the guides and adapted to coöperate with the suspender buttons on a pair of trousers for supporting the latter.

5. The combination with a suitable hanger having 115 longitudinally extending guides thereon, of slides adjustable relatively on said guides each composed of a single piece of sheet metal having an intermediate loop formed therein and slidably engaging the respective guide, the ends of the loop being adapted to have a binding engagement with the guide to retain the slide in adjusted position, and the ends of the strip being rolled to form bearings having axes arranged parallel to the direction of the guide, and a button engaging loop having a journal portion fitting the rolled portions of the strip.

6. In a garment hanger, the combination with a coat form having guides extending longitudinally thereon, of a pair of trousers-attaching devices each embodying a slide adjustable longitudinally of its respective guide, and a pair of arms carried by each slide having pointed stems adapted to coöperate with the material of the trousers, the pointed ends of the stems of the two slides being oppositely directed, and the enlargements surrounding the stems and adapted to engage the inner surface of the material of each leg of the trousers.

7. In a garment hanger, the combination with a coat form having guides toward the opposite ends extending

longitudinally thereof, of a pair of slides adjustable longitudinally of the respective guides each composed of a single piece of sheet metal having an intermediate loop to engage the guide, the metal being then folded to form 5 a pair of loops arranged parallel and adjacent to the intermediate loop, arms journaled in said pair of loops having outwardly directed ends adapted to engage within the legs of a pair of trousers, a band encircling the folded portion of the metal between the loops and the ends of the 10 metal being rolled to form journals, and button engaging

loops having journal portions fitted to turn in said rolled portions.

In testimony that I claim the foregoing as my own, I have hereto affixed my signature in the presence of two witnesses.

JOHN P. SUNDIN.
